United States Patent Office.

HARRISON OGBORN, OF RICHMOND, INDIANA.

Letters Patent No. 70,885, dated November 12, 1867.

IMPROVEMENT IN FANNING-MILL, GRAIN AND SEED-SEPARATOR.

The Schedule referred to in these Letters Patent and making part of the same.

TO ALL WHOM IT MAY CONCERN:

Be it known that I, HARRISON OGBORN, of Richmond, in the county of Wayne, and State of Indiana, have invented new and useful Improvements in a Combined Fanning-Mill and Grain and Seed-Separator; and I do hereby declare the following to be a full and clear description of the same, sufficient to enable others skilled in the art to which my improvement appertains to fully understand and use the same, reference being had to the accompanying drawings, making part of this specification, in which—

Figure 1 is a side elevation of my improved machine.

Figure 2 is a front elevation of the same.

Figure 3 is a section in line $\alpha\alpha$, fig. 2.

Figure 4 is a detached view of my device for giving rotary and reciprocating motion to the screens.

Figure 5 is a top view, and

Figures 6 and 7 modifications of the same.

Similar letters indicate corresponding parts in the several figures.

The nature of my invention consists, first, in the use of a board sliding in grooves in side plates, in place of the customary hopper, and in arranging an adjustable swinging end board in such a manner that the flow of the grain can be adjusted at pleasure by the position given to the same by means of a cam-lever; secondly, in novel means of giving either a rotary or endwise or side motion to the screens; thirdly, in combining with this apparatus for giving motion to the screens, a movement for giving to the lower screen an up-and-down motion; fourthly, in providing the fan with a vertical circular partition rim, to direct the two currents of air coming in at each side of the drum into one straight, strong blast; fifthly, in making the rear legs of the mill adjustable, so as to give more or less pitch to the screens; and lastly, in making the screens adjustable, in such a manner that the apparatus may, in a few moments, be so changed as to adapt itself readily to be used for cleaning either market or seed wheat, or small seed of any kind.

A A', in my drawings, represent the upright of a fanning-mill, supporting the cross-pieces B B', and the sides C and drum D. Secured to the cross-pieces B B' are the boards E, provided on their inner sides with two grooves, e e, in which the board F slides, and securely held together by the cross-piece G, over the top and under the bottom of which the grooves e run, coming together in front at an angle, so that the board F has more of a slant in the upper groove e than in the lower one. Pivoted at its top, to the rear of the side boards E, at a, is the swinging board H, which is adjusted by means of a cam-lever, E', and spur-pivoted at its front side, as shown in Figure 8. I is the vibrating shoe, hung in the rear from the standards A by the rods b, and in front from the standards A' by the rods c. The inner sides of this shoe I are provided with three different sets of grooves, the groove f running to the front end of the part I¹ of the shoe I, the grooves g running to the front end of the part I² of the shoe, and the groove h running the same as the grooves g, but horizontally. These grooves, with the exception of groove h, which is horizontal, converge towards each other at the rear of the machine. In the grooves f slide two screens, the front one, J, being a fine square-meshed one, and the rear one, K, a coarser one, as are also the screens L sliding in the grooves g. The groove h holds a board, M, which is not as wide as the depth of the part I² of the shoe I. A long meshed screen, N, is supported at its rear end by pins on its sides catching in ratchets i on the shoe, its front end resting on the bent portion, p', of a rod, p, as shown in fig. 3. The screens K L and the board M are held in place and prevented from sliding out of their respective grooves, f, g, and h, by means of the pin f¹, passing through the staples f², and through holes in the screens. At the lower end of the part I¹ of the shoe I, and resting against the front of its main part, is a trough, I³, across the whole width of the shoe, and directly under the screen J, so that the smaller grains of wheat, chess, cockle, &c., falling on to the upper grain-bottom, are shaken into the trough, and from it are thrown outside of the machine. The rear side board i³ of the trough I³, inside of the shoe-frame, is made adjustable by having holes in its bottom, sliding on pins on the bottom of the trough. It is also provided with holes on its inner face, corresponding in position with the holes in its bottom, so that it can be placed in a horizontal position, as shown in red lines in fig. 3. Inside of the drum D rotates the fan, its shaft o having its bearings on the standards A A', and provided with arms, P, to which wings Q are attached. At its centre it is provided with a circular rim, R, which acts as a guide to the currents of air coming in at each side of the drum, forcing them

together in one blast under and through the screws L and the whole shoe I. At one side of the fanning-mill, just inside of the drum D, is situated a gear-wheel, S, giving motion to the shaft o by means of the pinion T, and operated by the handle U. At the opposite side, just outside of its bearing on the standard A', the shaft o is provided with a belt-wheel, V, connected by a belt to the wheel W, which works loose on the vertical pin w in the plate X, secured to the side C. This wheel W is provided with three sets of holes, k k¹ k². Into one hole, k, is placed a pin, on the under side of the connecting-bar J, which is attached to the side of the vibrating shoe I, to which a horizontal circular motion is imparted when motion is given to the wheels V W. Attached to the wrist v, on the wheel V, is the rod m, linked to the rod m', which is connected to the lever n on the rod p. This rod p passes into the fanning-mill, and is bent horizontally to the front, directly under the centre of the forward end o of the screen N, in such a manner that when the rod p is moved by means of the wheel V and rods m m', the bent part p' of the rod p will strike the under side of the screen N, lifting it, and allowing it to drop again, thus imparting a quick up-and-down shaking motion to the screen; and as the lever n on the rod p is pressed forward, and the part p' is at its lowest position, resting on the lower grain-board D², the crank-rod m is enabled to finish its revolution without pressing the part p' of the rod p, by means of its being linked to the rod m', and thus enabled to bend. In place of the belt around the wheels W V, I sometimes use a rod, v', pivoted on the wrist v, the other end of which catches in either of the holes k¹ or k², giving either a side or end motion to the shoe, instead of a rotary one, as will be hereinafter more fully described. The ends of the standards A are made hollow, to receive square feet a¹ a², which are provided at their lower ends with metal points, a³. Pins c², passing through the end board C², the standards A, and the feet a², hold the latter in position, so that the rear of the fanning-mill may be lowered or raised, according to the pitch desired for the screens. The end board C² is placed across the bottom C¹ of the chess-box, and is provided with an opening, c³, flush with the bottom C¹, and closed by a door, c⁴. Through this opening the dirt, &c., can be cleaned whenever it becomes necessary.

The sliding doors G' G', over the openings of the drum, are provided with cleats g¹ g¹, which have pins g on their under side, to hold them securely in any position in which they may be placed, the pins g² preventing their slipping from their places through the shaking of the fanning-mill.

Seed wheat is cleaned in the following manner: The wheat is poured into the slide F, on which, by reason of its being of equal width the whole of its length, and not being narrower at its lower part, as it is usual to make the sides of square hoppers, the grain is spread out, thus preventing any possibility of its clogging. The rear opening being adjusted to the proper degree, by means of the tooth e¹ of the cam-lever E being made to catch into the rack e², the grain is free to fall into the upper end of the vibrating screen J. To regulate the flow of the grain, it is only necessary to raise the cam-lever E', swing the board H either nearer to or further away from the end of the slide E, and to refasten it by pushing the cam-lever E' down; and to feed still faster than the utmost opening of the swinging board H will allow, it is only necessary to draw the board F out in the grooves. The screen J is the market-wheat screen, and as the grain is shaken down on it most of the smaller wheat, chess, cockle, and other impurities, pass through its meshes and fall on to the upper grain-board I¹, and are carried into the trough I³, from which they are shaken to the outside of the fanning-mill, the wheat passing on to the screen K, provided with larger meshes, and falls through the same and the screens I on to the board M, the screens K and L arresting all coarser impurities. This board being provided with several holes to receive the pin f¹, can be adjusted nearer to or further from the rear end of the shoe, so that as the grain falls from the board on to the screen N, more or less of the remaining impurities are carried out by the blast from the fan. The grain has now fallen on to the lowest screen, N, which is provided with long narrow cross-meshes, and which is constantly shaken by the rod p. The smaller wheat and any still remaining impurities are jolted and sifted through the meshes of the screen on to the inclined bottom of the shoe, from which they fall into the chess-box C¹, and may, whenever necessary, be taken out through the opening C³, whilst the large, pure seed wheat is carried over the screen N and bottom grain-board D², on to the floor under the drum. To clean market wheat the screen N is taken out and laid aside, the screen J placed in its stead, the screen K taken out and also laid aside, and the board i³ of the trough I³ placed in the position as shown in red lines in fig. 3, thus forming a continuation of the upper grain-board I¹. To clean the finest seeds, such as timothy seed, the sliding doors G' of the drum are closed, and the screen J, in the place of the screen N, exchanged for a finer one.

Having thus described my invention, what I claim as new therein, and desire to secure by Letters Patent, is—

1. The trough I³, situated under and at the lower end of the upper grain-board, with a removable side, i³, substantially as and for the purposes described.
2. The combination of the adjustable trough I³, with the upper grain-board I¹, forming the bottom of the front part of the shoe I, and the adjustable screen J, substantially as and for the purposes described.
3. The combination of the upper grain-board I¹ with the adjustable side i³ of the trough I³, substantially as and for the purposes described.
4. A hopper, consisting of the side boards E, with converging grooves c, the sliding board F, and adjustable swinging board H, substantially as and for the purposes described.
5. The combination of the swinging board H, lever E, provided with a spur or tooth, e¹, and the rack e², substantially as and for the purposes described.
6. The vertical circular rim R, secured to the fannings Q, substantially as and for the purposes described.
7. The rod p, with its bent part p', and the lever n, substantially as and for the purposes described.
8. The rod p, in combination with the linked rods m and m', wrist v and wheel V, substantially as and for the purposes described.
9. The belt-wheel W, pivoted loosely on the pin w, and provided with three sets of holes, K, K¹, and K², for the purpose of giving either circular, side, or end motion to the shoe, substantially as and for the purposes described.

10. The arm *l*, rigidly attached to the shoe, by means of which motion is transmitted to the shoe, substantially as and for the purposes described.

11. The combination of the arm *l*, rigidly attached to the shoe, pulleys *V W*, and belt, to give circular motion to the shoe, substantially as and for the purposes described.

12. The combination of the arm *l*, pulleys *V W*, and rod *v'*, to give either side or end motion to the shoe, substantially as and for the purposes described.

13. The pins *g'*, on the cleats of the sliding doors *G'*, substantially as and for the purposes described.

The above specification of my improved fanning-mill, grain and seed-separator, signed this twenty-eighth day of February, 1867.

HARRISON OGBORN.
